Reproductions **1.1-1.14** show a first embodiment; Reproductions **1.10** and **1.11** are enlarged views of reproductions **1.5** and **1.6**, respectively; Reproductions **1.12-1.14** correspond to portions B, C and D in Reproductions **1.7-1.9**, respectively; Reproductions **2.1-2.15** show a second embodiment; Reproductions **2.11-2.12** are enlarged views of Reproductions **2.5** and **2.6**, respectively; and Reproductions **2.13-2.15** correspond to portions B, C and D in Reproductions **2.7**, **2.8** and **2.10** respectively. The product is used for hanging a hand-held vacuum cleaner and its attachments, and may provide charging function. The broken lines shown in Reproductions **1.7-1.9**, **2.7**, **2.8** and **2.10** of the hanger for handheld vacuum cleaner is for the purpose of illustrating the enlargements and forms no part of the claimed design. The broken lines shown in Reproductions **1.6** and **1.11** and the dark colored portions in Reproductions **2.6** and **2.12**

depict portions of the hanger for handheld vacuum cleaner that form no part of the claimed design.
